SIGHT FOR FIREARMS

Harold F. Mossberg, New Haven, Conn., assignor
to O. F. Mossberg & Sons, Inc., New Haven,
Conn., a corporation of Connecticut

Application November 30, 1937, Serial No. 177,233

5 Claims. (Cl. 33—53)

This invention relates to sights for firearms and more particularly to a ramp front sight having a plurality of differently shaped sight posts adapted to be readily and selectively positioned 5 for sighting purposes.

It is desirable that firearms be provided with quickly and readily interchangeable and differently shaped front sight posts and that the necessity of carrying these different posts separated 10 from the firearms be avoided. Front sights have been provided with a connected pair of differently formed sight posts mounted on and arranged to swing lengthwise of, the firearm to dispose either of them in sighting position. Such sights were 15 limited to two different forms of sight posts and required replacement to provide any form of post other than these two. It is contemplated, as one object of this invention, to provide a sight for a firearm which has more than two differently 20 shaped posts and wherein any one of these posts may be selectively and readily disposed in sighting position.

Among the other objects of this invention are; the provision in a sight for a firearm of a plurality 25 of differently shaped sight posts, each of which is individually movable into sighting position; means to locate and retain the selected and positioned sight post in position; a readily removable hood to cover the selected and positioned 30 sight post and to retain those not so positioned out of sighting position; and a common supporting means for the plurality of sight posts.

A further object is to provide an improved sight 35 for a firearm, which is relatively inexpensive to manufacture, simple in construction, compact, of pleasing appearance, and very efficient and durable in use.

With the above and other objects in view, which 40 will appear as the description proceeds, there has been illustrated in the accompanying drawing one form in which the invention may be conveniently embodied in practice.

In the drawing, wherein like reference characters 45 designate like parts throughout the several views:

Figure 1 is a side view of a firearm or gun having 50 a ramp front sight embodying the features and principles of this invention associated therewith;

Figure 2 is an enlarged side view of the sight shown in Figure 1;

Figure 3 is a front end view of the same;

Figure 4 is a still further enlarged sectional 55 view taken on line 4—4 of Figure 3;

Figure 5 is a cross-sectional view taken on line 5—5 of Figure 2; and

Figures 6, 7, 8, and 9 are detail front face views of the sight posts adapted for use with the sight of this invention.

The sight 11 of this invention commonly known as a ramp front sight is shown, in Figure 1, mounted on the forward end of the barrel 12, of a bolt action gun 13, in position for use in sighting the same in cooperation with the usual rear sight 14. The sight 11 is provided with a base block 15 secured to the barrel 12 by means of a dovetail plate 16 wedged into a corresponding dovetail slot 17 formed in the barrel 12, and a screw 18 passing through the base block 15 and threading into the plate 16, see Figure 4. The underside of the base block 15 is grooved lengthwise to fit the curvature of the barrel 12 and to insure that it will firmly seat thereon when it is clamped thereto by the cooperating screw 18 and plate 16.

A cylindrically shaped hood 19 is provided to cover the sight post of this sight and has a lengthwise slot formed in its bottom surface having opposing parallel edges 21 and 22 which are adapted to enter and slide in corresponding 25 grooves 23 and 24 respectively. The grooves 23 and 24 are provided one on either side of the base block 15 adjacent its upper surface. At the forward end of the hood 19, opposing fingers or lugs 25 and 26 are provided, being formed, for instance, by narrowing the slot at this point. The fingers 25 and 26 act as stops to limit the rearward movement of the hood 19 by engaging the forward end of the base block 15. The hood 19 may be readily moved forwardly to remove it from 30 the base block 15 as shown in dotted lines in Figure 2, for a purpose to be hereinafter described.

A plurality of sight posts 27, 28, 29, and 31, shown respectively in Figures 6, 7, 8, and 9 are provided, each having a different sighting shape 40 at its upper end, a hole 32 in its base portion 33, and a concave groove 34 formed in the bottom end surface of the base portion 33 which groove 34 forms spaced apart points 35 and 36. The posts 27, 28, 29 and 31 are arranged in face to face 45 abutting relation and are pivotally mounted upon an extending end 37 of a screw 38 which threads into the forward end of the base block 15, see Figure 4. The end 37 of the screw 38 is passed through the hole 32 in each of the posts 50 and extends beyond them to enter a hole 39 formed as a continuation of the threaded opening 40 in the base block 15 into which the screw 38 threads. The base block 15 is provided with a transversely directed slot 41, disposed substan- 55

tially at right angles to the hole 39 and in which the base portions 33 of the posts are disposed. A coiled spring 42 is disposed in the hole 39 and reacts between its bottom and the first of the post base portions 33 to press them together and against a shoulder 43 formed at the end of the threaded portion 44 of the screw 38.

A leaf spring 45, having its forward end 46 turned upwardly and clamped between the forward end of the base block 15 and the head 47 of the screw 38, extends rearwardly of the block 15, in a lengthwise slot 48 formed therein, into a position in under the posts 27-31 inclusive to resiliently engage the points 35 and 36 of the selected sight post to locate and firmly maintain it in sighting position. When a selected sight post is so positioned and firmly maintained in position by the leaf spring 45, the other posts are disposed in a downwardly and angularly disposed position, as shown in Figures 3 and 5, and are prevented from being swung into an upright position by the respective over-hanging edge 21, or 22, of the hood 19 and also prevented from inadvertently swinging upwardly into position by engagement of the leaf spring 45 with the adjacent side of the base portion 33.

When it is desired to change from one of the sight posts to another, the hood 19 is moved forwardly of the base block 15 to remove it therefrom and the selected sight post is swung transversely of the base block 15 upon the extending end 31 into an upright position, wherein the points 35 and 36 thereof will be engaged by the leaf spring 45 to locate and hold it in sighting position. The sight post replaced by the selected one will be swung transversely of the block 15 and downwardly to one side of the block 15 into either position of the sight posts 28 and 31 in Figure 3. Replacement of the hood 19, with its stop fingers 25 and 26 abutting the forward end of the block 15, will retain the downwardly swung sight posts against being swung into an upright position and forms a hood over the selected upright one.

While there has been illustrated and described above a specific form of sight embodying the features and principles of this invention it will be understood that the same may be embodied in other forms without departing from the spirit or essential attributes thereof. It is therefore desired that the present embodiment be considered in all respects as illustrative and not restrictive, and it will be further understood that each and every novel feature and combination thereof present in, or possessed by, the device herein disclosed, forms a part of the invention included in this application.

What is claimed as new and for which it is desired to secure Letters Patent, is:

1. A front sight for a firearm having a barrel, said sight comprising a base block seated on and extending along the barrel of said firearm, means to detachably clamp said block to the barrel, said block having a cross-slot formed therein, a plurality of juxtaposed differently shaped sight posts arranged one in back of the other with their lower end portions in the cross-slot in said block and being swingable into an upright position, each of said posts having a concave groove formed in its lower end surface to provide spaced apart points thereon, a leaf spring extending lengthwise of said block beneath the posts and having an end portion turned upwardly over an end of said block, a screw member threadingly disposed in

said block and having a portion extending through said posts to form a pivot pin therefore and a head portion to engage the upwardly turned end of said leaf spring to clamp it to said block end, said leaf spring being bowed upwardly to engage the points on said posts to firmly hold the selected post in upright position. 5

2. A front sight for a firearm having a barrel, said sight comprising a base block seated on the barrel of the firearm and extending along the same, means to detachably clamp said block to the barrel, said block having a cross-slot formed therein, a plurality of juxtaposed differently shaped sight posts arranged one in back of the other with their lower end portions in the cross-slot in said block and being swingable into an upright position, a pivot pin extending lengthwise of said block and through the lower end of each of said posts, a spring coiled about said pin and reacting between said block and said posts to press the posts together, and a leaf spring extending lengthwise of said block beneath the posts and between the block and the barrel of the firearm, said leaf spring being bowed upwardly intermediate its ends to react between the lower end 25 of a selected post and the barrel of the firearm to hold the selected post in upright position. 25

3. In a sight for a firearm, a base block, a plurality of individually swinging sight posts, a common leaf spring having a portion extending beneath said posts and adapted to act against the lower end of any selected one thereof to retain it in sighting position and a portion bent upwardly over the end of said base, and a screw threaded into said base and having an extension upon 30 which said sight posts are pivoted and also having a headed portion to clamp the bent up portion of said leaf spring against the end of said base. 35

4. In a sight for a firearm, a base block, a plurality of juxtaposed sight posts swingable crosswise of said base block to either side thereof, a common leaf spring having a portion extending beneath said posts and adapted to act against the lower end of any selected one thereof to retain it in sighting position, a common pivot member 40 for said posts extending lengthwise of said base block, and a spring reacting between said block and said posts to press said posts together axially with respect to said pivot member. 45

5. In a sight for a firearm, a base block, a plurality of sight posts, a pivot pin upon which said posts are mounted one in back of the other, said pin being mounted in said block with its axis extending parallel to the axis of the barrel of the firearm, said posts being swingable on said pin from a horizontal position at one side of said pin laterally across said block through an arc of 180 degrees to a horizontal position at the other side of said pin, each post having a sight portion on its upper end, and a flat leaf spring secured to said block and extending lengthwise along the barrel of the firearm below said posts, said spring being bowed upwardly intermediate its ends, and common means to secure said base block to the barrel of a firearm and to press said leaf spring against the barrel to tension the spring and cause it to react between the barrel and the lower end of said posts and thereby engage the lower end of a selected post when the selected post is in a vertical position to hold it in such position. 55 60 65 70
